UNITED STATES PATENT OFFICE.

JOHN J. FOLEY, OF HARTFORD, CONNECTICUT, ASSIGNOR TO HENRY REUBER, JR., AND HIMSELF, DOING BUSINESS AS THE ART LAMP AND NOVELTY COMPANY, OF HARTFORD, CONNECTICUT.

SHADE SUPPORT FOR LAMPS.

Application filed September 30, 1927. Serial No. 223,140.

My invention relates to the class of devices employed for supporting shades of various sorts, commonly used in connection with lamps, and an object of my invention, among 5 others, is to provide a support that shall be simple and inexpensive and also one capable of supporting a shade in a particularly efficient manner.

One form of device embodying my invention and in the construction and use of which the objects herein set out, as well as others, may be attained, is illustrated in the accompanying drawings, in which—

Figure 1 is a view in side elevation of a 15 lamp with my improved support attached thereto, the shade mounted on the support being shown in section.

Figure 2 is a view in elevation of the support.

20 Figure 3 is a view in elevation looking at the edge of the support.

Figure 4 is a top view of the support.

Figure 5 is a view in section on a plane denoted by the dotted line 5—5 of Figure 2.

25 In the accompanying drawings the numeral 6 denotes the standard of a lamp more especially of the electric type, and in connection with which my improved device is adapted for use, altho it will be understood that said

30 support is not limited to use with such lamps. A screw threaded stud (not shown) projects from the upper end of the standard in a manner common to devices of this class, this stud being adapted to receive a lamp 7 that is secured in place by means of interengaging screw threads on the lamp and stud.

35 My improved support, or "harp" as it is commonly known in the trade, comprises a base that is formed from sheet metal stamped 40 to shape and including a base plate 8, side parts 9 and sockets 10. This base is formed from a single piece of sheet metal that is properly shaped to provide material to be formed into the sockets 10.

45 Posts 11 of the support are formed from wire bent to desired shape, this shape preferably including bows 12 with short extensions 13 therefrom to receive the sockets 14 of a top comprising sides 15 and a top plate 16. The

of a neck 17 of a shade 18. This shaping of the sides 15 provides a secure seat for the shade 18, said sides in fact constituting such seat.

50 A screw stud 19 projects from the plate 16 and a cap 20 secured by a thumb nut 21 is formed to fit over the neck 17 and clamp said neck firmly against the sides constituting the seat 15, and thus securely fasten the shade in position.

55 As will be readily seen the sockets 10 and 14 are formed from wings extending laterally from the blanks from which the bottom and top are formed, and by constructing such bottom and top of sheet metal and providing 60 sockets to receive the posts that are formed from wire a very inexpensive shade support or harp is obtained that may be sold at a low cost and that, at the same time, most satisfactorily serves the ends for which it is 65 intended.

70 In the preferred form of construction the posts will generally be secured within the sockets 10 and 14 in any suitable manner, as by spot welding, but it will be understood 75 that this is not absolutely essential to my invention that contemplates a fit between the posts and sockets tight enough to serve this purpose.

75 It will also be noted that the base and top are duplicates, except for the size of the holes, through the top and base plates, and the posts 80 11 also being duplicates the entire support is made up of parts of two forms only.

85 It will also be noted that the sockets 10 and 14 are formed inwardly of the sides of the top and bottom whereby the ends of the posts 11 formed from wire abut against the inwardly extending parts of the top and bottom and consequently limit the distance between said 90 top and bottom after the posts have been cut for a specific form of harp or support.

95 In accordance with the provisions of the patent statutes I have described the principles of operation of my invention, together with the device which I now consider to represent the best embodiment thereof; but I desire to have it understood that the device shown is only illustrative and that the invention may be carried out by other means 100

and applied to uses other than those above set out.

I claim—

A shade support comprising a top and bottom member of like construction each having a transverse part and sides together forming a dish-shaped structure terminating in spaced

parallel sockets, posts mounted at their ends in the sockets and spread apart to provide a bulb clearance, a shade having a part thereof mounted on the sides of the top member, and retaining means for the shade engaged with the shade and top member. 10

JOHN J. FOLEY.
